RAILWAY TRAFFIC CONTROLLING
APPARATUS

Frank H. Nicholson and Harold W. Bryan, Penn
Township, Allegheny County, Pa., assignors to
The Union Switch & Signal Company, Swiss-
vale, Pa., a corporation of Pennsylvania

Application July 12, 1940, Serial No. 345,148

20 Claims. (Cl. 246—63)

Our invention relates to railway traffic controlling apparatus, and more particularly to apparatus of this type comprising train carried train controlling means governed by energy received from the track rails.

Train carried train controlling means governed by alternating current inductively received from the track rails is in general use, such alternating current being preferably coded or periodically interrupted at any one of several different code rates according to different traffic conditions. The train carried means includes receiving apparatus comprising inductors mounted on a train in inductive relation to the track rails for receiving electromotive forces corresponding in code to the code of the current flowing in the rails, and an electron tube amplifier or detector to the input or control side of which the inductors are connected and to the output side of which a code following relay is connected for operation of the relay at a rate corresponding to the code rate of the track rail current. Such code following relay controls a group of decoding relays through the medium of tuned circuits or filters, such tuned circuits or filters being proportioned to selectively energize the decoding relays at a condition different for each code rate at which the code following relay is operated. The decoding relays are used in turn to selectively govern a cab signal and train brake control equipment with the result that a particular signal aspect is displayed and a preselected train brake control is effected for each of the different traffic conditions for which a code rate is assigned. While alternating current of 100 cycles per second is preferably used alternating current of some other frequency or impulses of direct current may be used by proportioning the receiving apparatus for response to such currents. It is common practice to employ the code rates of 180, 120 and 75 cycles per minute to reflect clear, approach medium and approach traffic conditions, respectively, a fourth traffic condition of slow speed or caution being reflected by the absence of such coded current. When brake control equipment is governed by the decoding relays it is customary to interlock the manual brake control equipment with the automatic brake control equipment governed by the decoding relays, and to require a suitable acknowledgment on the part of a train operator of a change to a more restrictive control condition in order to prevent application of the brakes automatically.

Speed control equipment may also be provided, such speed control equipment comprising a speed

governor mounted on the train and operatively connected by suitable drive mechanism to a train axle or other moving part so that circuit controlling contacts of the governor are actuated at different preselected train speeds, a maximum train speed being usually prescribed for each of the different code rates, that is, for each of the different traffic conditions. The circuit controlling contacts of the speed governor are interposed in the circuits for the automatic brake control equipment in such a manner that an automatic application of the train brake is effected in the event the train speed exceeds the maximum speed prescribed for the traffic condition at which the decoding relays are at the time conditioned. When such automatic speed control is provided, it is desirable to provide a warning indication to the train operator when the train is operating at a speed above the maximum permissible speed and an automatic brake application may be effected so that the train operator may reduce the train speed by a manual application of the brakes or by shutting off the power or by both shutting off the power and making a manual application of the brakes, and in that way suppress an automatic brake application and retain full control of the train.

Furthermore, it has been proposed for such train control systems to provide electrical cut-out means wherewith the train carried equipment may be placed at an inactive or cut-out condition when the train moves into a territory where the track rails are not supplied with the necessary train control current, and which electrical cut-out means permits the automatic train control apparatus to be restored to an active condition when the train moves from such nontrain control territory back to a territory where the track rails are supplied with the necessary current. Also when the vehicle on which the train control apparatus is mounted is a motive power unit equipped with motive power control apparatus for operating such vehicle either end first, inductors are located at each end of the vehicle ahead of the wheels and directional means is provided wherewith only the inductors at the leading end of the vehicle are rendered effective.

Accordingly, a feature of our invention is the provision of novel and improved train carried train control apparatus for a four-indication four-speed control train control system.

Another feature of our invention is the provision in train carried train control apparatus of the type here contemplated of novel and improved speed warning indication means which is

actuated when the train is above the authorized speed and which means also includes a power-off switch circuit controller effective when operated because the train has exceeded the authorized speed to remove power from the master controller of the vehicle, thereby preventing the train operator from using power to accelerate to a higher speed.

Again, a feature of our invention is the provision of novel and improved timing means wherewith a delay time equal to the slow release period of a relay is inserted between the speed warning indication and the automatic application of the brakes and suppression of such automatic application of the brakes may be effected by the train operator taking suitable action to reduce the train speed.

Another feature of our invention is the provision in train carried train control apparatus of the type here involved of a novel and improved acknowledging circuit arrangement wherewith acknowledgment of the most restrictive indication only is required.

An additional feature of our invention is the provision of novel and improved electrical cut-out means wherewith the train carried train control apparatus is automatically placed at a cut-out or inactive condition when the train moves to non train control territory and is automatically restored to its active condition when the train again enters train control territory.

Also a feature of our invention is the provision of novel means wherewith the electrical cut-out means may be manually operated by the cooperation of two members of the train crew.

Also a feature of the invention is the provision of a novel circuit arrangement for controlling the timing relay through contacts of a power-off switch so that automatic release of an automatic brake application is prevented and the same procedure followed in suppression of an automatic brake application must be followed to re-energize the brake control magnet valve and permit the release of an automatic brake application.

The above features of our invention as well as other advantages which will become apparent as the specification progresses are attained by providing the usual train carried train control apparatus with a train operated speed governor having a plurality of different sets or groups of contacts, a speed warning relay which controls over its back contact a speed warning cab signal light, a slow release timing relay which controls over its front contact the usual brake control magnet valve, and a twin assembly speed warning whistle magnet valve. The magnet of one unit of the warning whistle magnet valve when energized causes a pneumatic power-off circuit controller or switch to be operated to a closed position and a whistle repeater valve to be actuated to a position where a warning whistle controlled by such repeater valve is silent, and when deenergized permits the power-off circuit controller to be actuated to an open position and the repeater valve to be moved to a position where the warning whistle is sounded. The magnet of this one unit is energized over a circuit having a plurality of multiple circuit paths each of which paths includes a front contact of a particular decoding relay, a contact of the speed governor contact group that corresponds to the same code rate as that at which such decoding relay is energized, and a resistor. The timing relay is connected in multiple with the

magnet of this one unit over contacts of the power-off switch controller. The warning relay is connected across the resistors over multiple circuit connections each of which connections includes a contact of the speed governor contact group having a contact interposed in the corresponding circuit path. Hence the warning relay is energized due to the voltage drop across the resistor interposed in the circuit path over which the magnet of this one unit and the timing relay are at the time energized. Thus when the train exceeds the speed prescribed for the traffic condition at which a particular decoding relay is selected, the warning relay and warning magnet valve are deenergized to effect a warning visual signal and a warning whistle but a delay time equal to the slow release period of the timing relay is interposed between the establishment of such warning indications and an automatic brake application.

Suppression of an automatic brake application is effected by providing an alternative circuit for the brake control magnet valve by which such magnet valve may be energized when the timing relay is released and which alternative circuit preferably includes a contact closed at the off position of the master controller of the vehicle in series with a contact of a pneumatically operated suppression switch closed when the manual brake valve is moved to a brake application position.

The timing relay is also controlled either through a back contact of a relay connected in multiple with the most restrictive cab signal unit or through a front contact of the usual acknowledging relay so that when the most restrictive code rate is received the timing relay is disconnected from the current source and it is necessary for the train operator to make the usual acknowledgment of such restrictive indication and pick up the acknowledging relay in order to reconnect the timing relay to the current source.

The second unit of the speed warning whistle magnet valve controls the usual acknowledging whistle.

For automatic electric cut-out of the train control apparatus when the train moves to non train control territory, an additional tuned circuit and decoding relay are provided. This additional tuned circuit is adjusted for response to a code rate materially different from the 180, 120 and 75 traffic controlled code rates and which may be, for example, of the order of 240 cycles per minute. When current of the 240 code rate is received from a special track circuit located adjacent the point where the train passes to non train control territory and the special cut-out decoding relay is energized and picked up such cut-out decoding relay is retained energized by a stick circuit controlled over back contacts of the traffic controlled decoding relays. Such special cut-out decoding relay when picked up completes special circuits for the timing relay, warning relay and the magnet valve of the first unit of the speed warning whistle magnet valve, and also completes a circuit for a special cab signal unit to indicate operation of the train outside of train control territory. A manually operable cut-out switch is located at a point remote from the usual acknowledging switch and a circuit is provided for picking up the special cut-out decoding relay by a local circuit over contacts controlled by both the cut-out switch and the usual acknowledging switch, so that when two mem-

bers of the train crew, one at the cut-out switch and one at the acknowledging switch, operate these two switches at the same time the special cut-out relay is picked up to establish the cut-out condition of the train control apparatus. An indication light is provided near the cut-out switch to indicate to the operator thereof the position of the usual acknowledging switch.

To effect directional control a directional circuit controller is mounted on the vehicle and provided with a contact over which only the train carried inductors at the leading end of the vehicle are connected to the input side of the amplifier. Preferably, such directional circuit controller is automatically governed by pneumatic relays connected to the train control air pressure supply pipe in the manner covered by a copending application, Serial No. 345,127, filed July 12, 1940, by W. A. Oehlschlager for Railway traffic controlling apparatus, and wherewith the pneumatic relay corresponds to the end from which the vehicle is to be operated only if supplied with pressure.

We will describe one form of apparatus embodying our invention, and will then point out the novel features thereof in claims.

The accompanying drawings when taken together with Fig. 1a placed at the left of Fig. 1b are diagrammatic views showing a preferred form of apparatus embodying our invention when used with train carried apparatus of a four-indication four-speed control train control system.

Referring to the drawings, a first pair of inductors 2a and 2b are mounted at one end of a railway vehicle on which the apparatus of the drawings is mounted, in inductive relation to the track rails 1a and 1b, respectively, and a second pair of inductors 3a and 3b are mounted at the other end of the vehicle in inductive relation to the track rails 1a and 1b, respectively. It is to be understood that the vehicle on which these inductors are mounted is to function as the motor unit of the train and is provided with a master controller, a manual brake valve and other necessary power equipment at each end of the vehicle for operation of the vehicle either end first. The inductors of each pair are connected together in the usual manner and are adaptable of being included in the input or control circuit of an amplifier AM by means of a contact member of a directional circuit controller DCC, the arrangement being such that when contact member 4 is actuated to a left-hand position to close a contact 4-5, the inductors 2a and 2b are connected to the amplifier AM and when the contact member 4 is moved to a right-hand position to close a contact 4-6 the inductors 3a and 3b are connected to the amplifier AM.

The directional circuit controller DCC is pneumatically actuated. When the usual cut-out valve CV1 located at one end of the vehicle, that is, at the same end of the vehicle as inductors 2a and 2b are mounted, is turned to supply air pressure to the train control supply pipe 31, through a check valve 1, pressure is supplied to the diaphragm chamber of a pneumatic relay 8 and contact members 4, 9 and 10 of controller DCC are actuated to the left-hand position as viewed in the drawings, inductors 2a and 2b being thereby connected to the amplifier over contact member 4. When a second cut-out valve CV2 located at the other end of the vehicle is set to supply pressure to the train control supply pipe 31 pressure is supplied to the diaphragm chamber of a pneumatic relay 12 and contact members 4, 9 and 10 are actuated to the right-hand position, and inductors 3a and 3b are

connected to the amplifier over contact member 4. The contact members 9 and 10 of controller DCC are used to control the connections of a current source such as a generator G and battery 13 to terminals B32 and C, and from which terminals 5 current is taken for the various circuits. Generator G is driven by a motor CM and is arranged to supply current of a convenient voltage, such as 32 volts. Battery 13 serves as a stand-by current source. Hence when the vehicle is to be operated 10 with the end at which inductors 2a and 2b are mounted as the leading end and the cut-out valve CV1 located at the same end of the vehicle is set to supply air pressure to the train control supply pipe 31, the directional controller DCC is operated 15 to the position where inductors 2a and 2b are connected to the amplifier but that when the vehicle is to be operated with the other end first and the cut-out valve CV2 is set to supply pressure to the train control supply pipe 31, the directional controller DCC is operated as required to connect the inductors 3a and 3b to the amplifier. Also, energy for the various circuits is applied to terminals B32 and C when either relay 8 or 12 is supplied with pressure.

The amplifier AM may be any one of several well-known forms and is shown conventionally. A code following relay MR is connected to the output side of amplifier AM and is operated in the well-known manner at a rate corresponding 30 to the code rate of the current flowing in the track rails and picked up from the track rails by the inductors.

Code following relay MR controls the usual three decoding relays A, R and L in the well-known manner and it is sufficient for the present application to point out that when relay MR is operated, direct current is supplied over contact member 14 of relay MR first to one half and then to the other half of primary winding 15 of a decoding transformer T1 and electromotive forces of a frequency corresponding to the rate at which relay MR is operated are in turn applied to tuned circuits 16 and 21, the arrangement being such that relay A which is coupled to circuit 16 is effectively energized and picked up only when relay MR is operated at the 180 code rate and relay R which is coupled to circuit 21 is energized and picked up when relay MR is operated at the 120 code rate. The electromotive forces induced in 45 secondary winding 18 of decoding transformer T1 are rectified at contact member 119 of relay MR and unidirectional current is supplied to decoding relay L to effectively energize and pick up relay L when relay MR is operated at either the 180, 120 50 or 75 code rate. As here shown the decoding relay R is also provided with an alternative energizing circuit which includes terminal B32 of the current source, front contact 20 of relay A, a resistor 21, winding of relay R, front contact 22 of relay A, 60 wire C1, back contact 23 of a relay P to be later described, and terminal C of the current source. It follows that when current of the 180 code rate is picked up from the track rails decoding relays A and L are energized due to the operation of relay 65 MR and relay R is energized and picked up due to its alternative circuit; when current of 120 code rate is picked up from the track rails decoding relays R and L are energized and picked up due to the operation of relay MR and relay A is released; 70 and when current of the 75 code rate is picked up from the rails relay L is energized and picked up due to the operation of relay MR and relays R and A are released.

An additional tuned circuit 19 is also connected 75

across primary winding 15 of decoding transformer T1 and is tuned to resonance at the frequency of the electromotive force effected by operation of relay MR at some rate materially different from the traffic controlled rates of 180, 120 and 75. Such additional code rate may, for example, be of the order of 240 cycles per minute. A cut-out decoding relay P is coupled to the tuned circuit 19 and is effectively energized and 10 picked up only when relay MR is operated at the code rate of 240. Decoding relay L may be picked up at the special code rate of 240 cycles per minute but the energizing of the traffic controlled decoding relay L at such time serves no 15 useful function, as will appear later in the specification.

The form of trackway apparatus for supplying to the rails current coded at different code rates in response to different traffic conditions is immaterial and it may be that covered by the United States Letters Patent No. 1,986,679, granted January 1, 1935, to L. V. Lewis for Railway traffic controlling apparatus, and wherein alternating current coded at the code rates of 180, 120 and 25 80 (75) is supplied to the track rails of a section in response to clear, approach-restricted (approach-medium), and approach traffic conditions in advance of such track section, respectively, and which current is shunted away from a following train by a leading train.

At a point where a train is to move from train control territory to nontrain control territory, a special track circuit would be provided for supplying the special 240 code rate for operating the 30 relay P. Special circuits at points where a train moves from train control territory to non train control territory are well-known and the special track circuit for providing the 240 code rate would be in accordance with usual practice since 40 its specific arrangement forms no part of our invention.

Decoding relays A, R and L govern the operating circuits for two cab signals one placed at each end of the vehicle near the position of the 45 train operator. The operating circuits of the two cab signals are arranged in parallel and the cab signal CS located at the same end of the vehicle as inductors 2a and 2b only is shown in the drawings for the sake of simplicity since the 50 second cab signal at the other end of the vehicle is a duplication of cab signal CS and a description of the circuits for signal CS is sufficient for an understanding of the circuits for both of such cab signals. Cab signal CS may take different 55 forms and is shown as a color light signal capable of displaying a distinctive aspect for four different traffic and speed conditions, a speed warning condition and a cut-out or non-active condition. The four different traffic and speed condition aspects are displayed by four signal units 60 designated by the reference characters 35, 25, 17 and 11. The speed warning condition is displayed by a signal unit W and the cut-out condition is displayed by a signal unit NS. Preferably these signal units of cab signal CS when 65 illuminated display a distinctive color and in addition the four units 35, 25, 17 and 11 display a corresponding numeral. The respective color of these four signal units indicates the traffic 70 condition in advance and the numeral designates the prescribed maximum speed for the corresponding traffic condition. For example, the signal unit 35 when illuminated displays a green color to indicate clear traffic conditions in advance, and the numeral 35 to indicate a maxi-

mum prescribed speed of 35 miles per hour for clear traffic conditions. Likewise signal unit 25 when illuminated displays a green over a yellow color and the numeral 25, the green over yellow color indicating approach-medium traffic conditions in advance, and the numeral 25 indicating the maximum prescribed speed of 25 miles per hour for approach-medium traffic conditions. Again, illumination of the signal unit 17 displays a yellow color and the numeral 17, the yellow color indicating approach traffic conditions in advance and the numeral 17 indicating the prescribed maximum speed of 17 miles per hour for approach traffic conditions. The illumination of signal unit 11 displays a red color to indicate slow or caution traffic conditions and the numeral 11 to indicate the prescribed maximum speed of 11 miles per hour. It is to be understood, of course, that our invention is not limited to such cab signal indications and train speeds 20 for the different traffic conditions but such cab signal indications and prescribed train speeds have been found useful where dense traffic conditions prevail. The color of the indications displayed by signal units NS and W will be referred 25 to later in the specification.

Referring specifically to the operating circuits by which the traffic controlled decoding relays govern the traffic controlled signal units of cab signal CS, when decoding relay A is picked up in 30 response to the clear 180 code rate an operating circuit can be traced from terminal B32 over front contact 20 of relay A, wire A1, lamp of signal unit 35 of cab signal CS, wire NA, front contact 22 of relay A, wire C1, back contact 23 of 35 relay P and terminal C, and the signal unit 35 is illuminated. When relay R is picked up and relay A is released in response to the approach-medium 120 code an operating circuit is formed from terminal B32 over back contact 24 of relay 40 A, front contact 26 of relay R, wire R1, lamp of signal unit 25, wire NR, front contact 28 of relay R, back contact 29 of relay A, wire C1 and back contact 23 of relay P to terminal C, and signal unit 25 is illuminated. Again when relay L is 45 picked up and relays A and R are released in response to the approach 75 code, an operation circuit extends from terminal B32 over back contacts 24 and 30 of relays A and R, respectively, back contact 51 of a relay SP to be referred to, 50 front contact 32 of relay L, wire L1, lamp of signal unit 17, wire NL, front contact 33 of relay L, back contacts 34 and 29 of relays R and A, respectively, wire C1 and back contact 23 of relay P to terminal C, and signal unit 17 is illuminated. 55 When the train is following another train in the track section and the coded rail current is shunted by the leading train and the decoding relays A, R and L are all released, an operating circuit is formed from terminal B32 over back 60 contacts 24, 30, 51 and 36 of relays A, R, SP and L, respectively, wire S1, back contact 37 of relay P, wire SK and lamp of signal unit 11 to terminal C, and signal unit 11 is illuminated. It is to be noted in connection with the operating circuit 65 for signal unit 11 that when relay SP is picked up in a manner to later appear, the back contacts 51 and 36 of relays SP and L are shunted by a connection completed at front contact 60 of relay SP.

A relay S, an acknowledging relay SP and a manually operable acknowledging switch ACK are associated with the decoding relays. Acknowledging switch ACK is mounted at the same end of the vehicle as cab signal CS and in a po- 75

sition for convenient operation by the train operator. Relay S is in effect energized in multiple with the slow speed or caution signal unit 11, the left-hand terminal of the winding of relay S being connected to terminal B32 over wire S1 and back contacts 24, 30, 51 and 36 of relays A, R, SP and L, respectively, the same as signal unit 11, and the right-hand terminal of the winding of relay S being connected to terminal C over back contacts 50, 34 and 29 of relays L, R and A, respectively, wire C1 and back contact 23 of relay P. The acknowledging relay SP is preferably of the type capable of being picked up over its back contact and is provided with a pick-up and a stick circuit both of which circuits are governed by the acknowledging switch ACK and the decoding relays. The pick-up circuit extends from terminal B32 over back contacts 24, 30, 51 and 36 of relays A, R, SP and L, respectively, wire S1, contact 52 of switch ACK when that switch is depressed, wire SP1, a top winding of relay SP, wire NSP and contact 53 of switch ACK when depressed to terminal C. With relay SP picked up and switch ACK returned to its normal position the stick circuit for relay SP is formed from terminal B32, over contact 54 of switch ACK, wire B2, back contact 55 of relay P, back contacts 56, 57 and 58 of relays A, R and L, respectively, front contact 59 of relay SP, lower winding of relay SP, back contacts 50, 34 and 29 of relays L, R and A, respectively, wire C1 and back contact 23 of relay P to terminal C. Again it is to be noted that front contact 60 of relay SP completes a shunt path around back contacts 51 and 36 of relays SP and L. Thus when slow traffic conditions prevail, relay S is at once picked up and acknowledging relay SP may be picked up by the operator depressing the switch ACK and then restoring the switch to its normal position. The function of acknowledging relay SP and relay S will appear hereinafter. Since the vehicle is to be operated either end first, a second acknowledging switch similar to switch ACK is provided at the other end of the vehicle and the circuits for acknowledging relay SP are governed by this second switch in substantially the same manner as switch ACK governs the circuits for relay SP but such second switch is omitted from the drawings for the sake of simplicity.

Automatic application of the train brakes is effected by a brake control magnet valve MV and a brake application valve BA, both of which may be of any one of the several well-known structures for such devices and may be of the structure disclosed in the aforementioned copending application, Serial No. 345,127, and it is sufficient for this application to point out that when magnet valve MV is energized to close a valve 38 and open a valve 39, pressure is built up on both sides of the piston 40 of the brake application valve BA and the piston 40 is held at its brake release position by means of the usual biasing spring, but that when magnet valve MV is deenergized to open valve 38 and close valve 39, the left-hand chamber of the brake application valve BA is exhausted and piston 40 is forced to its brake application position.

The magnet valve MV is energized over either a normal circuit or an alternative circuit. The normal circuit includes terminal B32, front contact 91 of a timing relay TR to be referred to later, wire M, winding of magnet valve MV, wire NM, front contact 92 of relay TR and terminal C. The alternative circuit includes terminal B32,

contact 54 of acknowledging switch ACK at its normal position, a contact 102 of the master controller of the vehicle located at the same end of the vehicle as cab signal CS and closed only at the power off position of the master controller, 5 contact 103 of a suppression switch SR to be later described, wires M1 and M, winding of magnet valve MV, wires NM and NM1, a second contact 104 of suppression switch SR, a second contact 105 of the master controller, and terminal C. 10 Suppression switch SR is of the usual pneumatic relay type and is connected to the manual brake control valve in such a manner that pressure is admitted to the diaphragm chamber of switch SR when the manual brake valve is moved to a 15 brake application position and contacts 103 and 104 are closed, but that when the brake valve is moved to a brake release or running position the diaphragm chamber of relay SR is exhausted to atmosphere and contacts 103 and 104 are open. 20

Hence magnet valve MV is energized and the brake release position is effected for the automatic brake application valve BA when timing relay TR is energized closing front contacts 91 and 92 and an automatic application of the train 25 brake is effected when timing relay TR is released unless the master controller is set at its power off position and the suppression switch SR is actuated because the manual brake valve has been set at a brake application position. 30

A pneumatic actuated power off switch controller PS and a speed warning repeater valve PV are controlled by air pressure supplied from the train control supply pipe 31 through one unit of a twin assembly speed warning whistle 35 magnet valve AMV, the power off switch controller PS being also controlled by the slide valve of the brake application valve BA. The specific structures of the three devices PS, PV and AMV form no part of our invention and it is sufficient 40 to point out that when magnet 61 of a first unit of the magnet valve AMV is energized to close valve 62 and open valve 63 pressure from the train control supply pipe 31 is admitted to pipe 64 leading to the piston chamber of repeater 45 valve PV and also through port 41 of the slide valve of the brake application valve BA to pipe 65 and thence to the piston chamber of the power off switch controller PS. Such pressure causes piston 66 of switch controller PS to be forced 50 upward against the force of bias spring 67 and contacts 44, 45, 46 and 47 are raised to a closed position. When magnet 61 of the first unit of magnet valve AMV is deenergized to open valve 62 and close valve 63, the pressure of the supply 55 pipe 31 is shut off and pipe 64 is connected to an exhaust port with the result that the pressure in the piston chamber of the switch controller PS is exhausted to atmosphere and the contacts 44 to 47, inclusive, are moved under the force of the 60 bias spring 67 to an open position. Also the piston chamber of switch controller PS is exhausted and the contacts 44 to 47, inclusive, are opened when brake application valve RA is actuated to a 65 brake applying position and connects pipe 65 to an exhaust port. The contacts 44 and 45 are used to govern the circuit of timing relay TR, as will shortly appear, and the contacts 46 and 47 are interposed in the power supply to the master controller of the vehicle so that when contacts 46 70 and 47 are opened the motive power for the vehicle is interrupted.

Pressure supplied from pipe 64 to the piston chamber of repeater valve PV forces piston 68 to the right as viewed in the drawings against the 75

force of the bias spring and a valve 69 is closed to blank the supply of pressure from supply pipe 31 to a pipe 70 leading to a speed warning whistle 71 located at the same end of the vehicle as 5 cab signal CS. Pipe 70 is connected to an exhaust port by a valve 77 when pressure is thus applied to piston 68. When the pressure of pipe 64 is exhausted, piston 68 of repeater valve PV is forced to the left as viewed in the drawings to 10 close valve 77 and open valve 69, and pressure from supply pipe 31 flows through pipe 70 to whistle 71, and whistle 71 is caused to sound a warning indication. It is to be seen, therefore, that when magnet 61 of the speed warning magnet 15 valve AMV is energized the power off switch controller PS is held closed unless the automatic brake application valve BA has been operated, and repeater valve PV is operated to cause the warning whistle 71 to be silent, but that when magnet 61 is deenergized the power off switch controller PS is operated to its open position to 20 interrupt the motive power and to open the circuit for the timing relay, and repeater valve PV is operated to cause pressure to be supplied to 25 the warning whistle 71, causing that whistle to sound.

When magnet 72 of the other or second unit of 30 the speed warning whistle magnet valve AMV is energized in a manner to later appear to actuate a poppet valve 73 pressure is admitted from supply pipe 31 to a pipe 74 leading to an acknowledging whistle 76 which is also located at the same end of the vehicle as cab signal CS and 35 whistle 76 is thereby sounded. When magnet 72 is deenergized valve 73 is actuated to blank the supply of pressure to pipe 74 and the acknowledging whistle 76 is silent. The two whistles 71 and 76 form two audible signals and would be of 40 different tones to provide distinctive audible signals. In actual practice whistles 71 and 76 would be duplicated at the other end of the vehicle, such duplication of whistles being supplied with pressure through pipes branching from 45 pipes 70 and 74.

45 The apparatus also includes a speed governor GV. This speed governor would be operatively connected to a train axle or other moving part through the medium of suitable drive mechanism, several such drive mechanisms being well-known to the art. This speed governor may, for 50 example, be of the structure covered in the application for Letters Patent of the United States, Serial No. 205,276, filed April 30, 1938 by H. L. Bone and J. W. Livingston for Speed responsive devices.

The speed governor GV is provided with four 55 different groups of contacts, each group consisting of three separate contacts and the contacts of each group of contacts being set for operation at preselected speeds of the vehicle. For example, the contacts 80a, 80b and 80c of the first group of contacts are set for operation from a biased closed position to an open position at train speeds of the order of 35 miles per hour 60 which is the maximum speed prescribed for clear traffic conditions. For reasons to shortly appear there is a speed differential between contact 80a and contacts 80b and 80c, contact 80a being set to open at 35 miles per hour and contacts 80b 65 and 80c being set to open at 36 1/4 miles per hour. The contacts 81a, 81b and 81c of the second group of contacts are set for operation from a biased closed position to an open position at train speeds of the order of 25 miles per hour, 70 which speed is the maximum prescribed speed 75

for approach-medium traffic conditions. A speed differential is likewise provided for this group of contacts, contact 81a being set to open at 25 miles per hour and contacts 81b and 81c being set to open at 26 miles per hour. Again, the 5 contacts 82a, 82b and 82c of the third group of contacts are set for operation from a biased closed position to an open position at train speeds of the order of 17 miles per hour, which is the maximum prescribed speed for approach 10 traffic conditions; a speed differential being provided with contact 82a set to open at 16 1/2 miles per hour and contacts 82b and 82c set to open at 17 1/2 miles per hour. The contacts 83a, 83b and 83c of the fourth group of contacts are set 15 for operation from a biased closed position to an open position at train speeds of the order of 11 miles per hour, which is the maximum prescribed speed for slow or caution traffic conditions, a speed differential being provided by contact 83a 20 being set to open at 10 miles per hour and contacts 83b and 83c being set to open at 11 miles per hour.

The contacts of each group of contacts of the speed governor GV are interposed with certain 25 contacts of the decoding relays in a circuit which controls magnet valve 61 of the first unit of the speed warning whistle magnet valve AMV, the timing relay TR and a speed warning signal relay WL. That is, magnet 61 and relays TR and 30 WL are controlled over a circuit having a plurality of multiple circuit paths each of which circuit paths includes a front contact of a particular one of the decoding relays and the contacts of the speed governor contact group that is 35 assigned to the same traffic condition or code rate as that at which that particular decoding relay is energized. When clear traffic conditions exist and decoding relay A is picked up in response to the clear 180 code, a circuit can be 40 traced from terminal B32 over contact 54 of acknowledging switch ACK, wire B2, back contact 55 of relay P, front contact 84 of decoding relay A, wire AG, contact 80b of the first contact group of speed governor GV, a resistor AG1, 45 wire SW, winding of magnet 61, wire NSW, contact 80c of the first contact group of speed governors GV, front contact 42 of relay A and to terminal C. The winding of relay WL is connected across resistor AG1 over a connection 50 that can be traced from the right-hand terminal of the winding of relay WL over wires SW1 and SW to the left-hand end of resistor AG1, and from the right-hand end of resistor AG1 over contacts 80b and 80a in series and wire 85 to 55 the left-hand terminal of winding of relay WL. Timing relay TR is connected in multiple with the winding of magnet 61 by a connection branching from wire SW over contact 44 of the power off switch controller PS, either back contact 86 of relay S or front contact 87 of relay SP, winding of relay TR, either back contact 88 of relay S or front contact 89 of relay SP, and contact 45 of the power off switch controller PS to wire NSW. It is to be seen, therefore, that 60 under clear traffic conditions and with decoding relay A picked up the magnet 61 and timing relay TR are energized in parallel over a circuit path including a front contact of relay A, contacts of the first group of speed governor contacts and resistor AG1, and relay WL is connected across resistor AG1 over contacts of the same group of contacts of the speed governor, and is energized due to the voltage drop across resistor AG1. Magnet 61 when energized con- 65 70 75 75

trols the power off switch controller PS and repeater valve PV in the manner already explained and relay TR when energized controls the brake control magnet valve MV as previously explained. Relay WL controls at its back contact 50 a simple circuit for the warning signal unit W of cab signal CS, the circuit being completed over wire WI. Hence signal unit W is dark as long as relay WL is energized and is illuminated 10 when relay WL is released. It is also to be noted that this circuit path for energizing magnet 61 and relays TR and WL under clear traffic conditions is completed at the first group of speed governor contacts when the vehicle does 15 not exceed the speed of 35 miles per hour as prescribed for clear traffic conditions, and when the speed of 35 miles per hour is reached contact 80a is opened to deenergize relay WL and when the speed of 36 1/4 miles per hour is reached 20 contacts 80b and 80c are opened to deenergize magnet 61 and relay TR.

In the event approach-medium traffic conditions exist and decoding relay R is picked up and decoding relay A is released, a second circuit 25 path extends from terminal B32 over contact 54 of acknowledging switch ACK, wire B2, back contact 55 of relay P, back contact 56 of relay A, front contact 93 of decoding relay R, wire RG, contact 81b of the second group of contacts 30 of speed governor GV, a resistor RG1, wire SW, winding of magnet 61, wire NSW, a second contact 81c of the second group of contacts, front contact 94 of decoding relay R and back contact 95 of relay A to terminal C. Relay WL is connected 35 across resistor RG1 over a connection including contacts 81a and 81b of the second group of speed governor contacts as will appear from an inspection of the drawings and relay WL is energized due to the voltage drop across resistor 40 RG1. Timing relay TR is connected in multiple with the winding of magnet 61 over contacts 44 and 45 of the power off switch controller PS the same as under clear traffic conditions. Again it is to be noted that under approach-medium 45 traffic conditions magnet 61 and relays TR and WL are energized when the train speed is below 25 miles per hour, and because of the speed differential when the speed of 25 miles per hour is reached contact 81a opens to deenergize relay WL and when the speed of 26 miles per hour is reached contacts 81b and 81c are opened to deenergize magnet 61 and relay TR.

Under approach traffic conditions and with decoding relay L picked up and relays A and R released, a third circuit path is completed and which circuit path is the same as the second path up to back contact 56 of relay A, thence over back contact 57 of relay R, front contact 96 of decoding relay L, wire LG, contact 82b of the third group of contacts of speed governor GV, a resistor LG1, wire SW, winding of magnet 61, wire NSW, a second contact 82c of the third group of contacts, front contact 97 of decoding relay L, and back contacts 98 and 99 of relays 55 R and A, respectively, to terminal C. Relay WL is connected across resistor LG1 over a connection which includes contacts 82a and 82b of the third group of speed governor contacts, and timing relay TR is connected in multiple with the winding of magnet 61 the same as in the previous cases. It follows that under approach traffic conditions magnet 61 and relays TR and WL are energized and picked up as long as the vehicle speed does not exceed that at which the 60 contacts of the third group of speed governor

contacts are set for operation, but that when the speed of 16 1/2 miles per hour is reached contact 82a is opened to deenergize relay WL and when the speed of 17 1/2 miles per hour is reached contacts 82b and 82c are opened to deenergize 5 magnet 61 and relay TR.

Under slow traffic conditions, that is, the most restrictive traffic condition, a fourth circuit path is completed for magnet 61 and relays TR and WL. This fourth circuit path extends from terminal B32 over back contacts 24, 28, 51 and 36 of relays A, R, SP and L, respectively, wire SI, front contact 89 of relay S, wire SG, contact 83b of the fourth group of contacts of speed governor GV, a resistor SG1, wire SW, winding of 15 magnet 61, wire NSW, contact 83c of the fourth group of contacts, back contact 100 of relay P, and back contacts 101, 98 and 95 of relays L, R and A, respectively, to terminal C. If acknowledging relay SP is picked up then its front contact 89 forms a shunt path around back contact 51 of relay SP and back contact 36 of relay L for this fourth circuit path. Relay WL is connected across resistor SG1 over contacts 83a and 83b of this fourth group of contacts and is energized due to the voltage drop across resistor SG1, and timing relay TR is connected in multiple with the winding of magnet 61 as in the previous cases. Hence under this most restrictive traffic condition when all the decoding 20 relays A, R and L are released, the magnet 61 and relay TR and WL are energized when the train speed is below that at which the contacts of the fourth group of contacts of speed governor GV are set for operation. That is, when the speed 25 of 10 miles per hour is reached contact 83a is opened to deenergize relay WL and when the speed of 11 miles per hour is reached contacts 83b and 83c are open to deenergize magnet 61 and relay TR.

Cut-out decoding relay P, as previously explained, is effectively energized and picked up through tuned circuit 19 in response to operation of relay MR at a 240 code rate, which code rate is supplied from a special short track section 30 located at each point where the vehicle may leave train control territory for non train control territory, and relay P when picked up automatically effects a cut-out condition for the train carried train control apparatus. Relay P 35 in order to retain the apparatus in its cut-out position while the vehicle operates over nontrain control territory, is further provided with a stick circuit by which it is retained picked up after a train moves beyond the special track circuit, 40 the traffic control decoding relays A, R and L being, of course, all deenergized and released while the vehicle occupies nontrain control territory. This stick circuit for relay P involves terminal B32, back contacts 24, 30, 51 and 36 of 45 relays A, R, SP and L, respectively, wire SI, front contact 100 of relay P, wire P2, normally closed contact 107 of a manually operable cut-out switch CO to be later referred to, wire P1, resistor 103, winding of relay P, wire NP, front 50 contact 108 of relay P, back contacts 101, 98 and 95 of relays L, R and A, respectively, and terminal C. When cut-out relay P is picked up the NS signal unit of cab signal CS is illuminated 55 to display a special purple color as an indication 60 of the cut-out condition of the apparatus. The operating circuit for signal unit NS branches from wire P2 of the stick circuit of relay P through signal unit NS and joins the stick circuit of relay P at wire NP. Relay P when picked 65 up illuminates the NS signal unit of cab signal CS as an indication 70 of the cut-out condition of the apparatus. The operating circuit for signal unit NS branches from wire P2 of the stick circuit of relay P through signal unit NS and joins the stick circuit of relay P at wire NP. Relay P when picked 75

up completes an alternative circuit for energizing magnet 61 of the magnet valve AMV and relay WL in series, this alternative circuit including terminal B32, contact 54 of acknowledging switch ACK, wire B2, front contact 110 of relay P, wire 85, winding of relay WL, wires SW1 and SW, winding of magnet 61, wire NSW and front contact 111 of relay P to terminal C. Since the power off switch controller PS is closed when magnet 61 is energized and since timing relay TR is connected across wires SW and NSW over contacts 44 and 45 of controller PS, the timing relay TR is also retained energized when the cutout relay P is picked up.

In describing the operation of the apparatus it is to be pointed out that the relays, valves and signal units are shown in Figs. 1a and 1b deenergized and inactive. It will be assumed that the vehicle is to be operated with the end at which cab signal CS and whistles 71 and 76 are located as the leading end. As the first step in placing the train control apparatus in service cut-out valve CV1 is set to supply air pressure to the train control supply pipe 31. Pressure is at the same time supplied to pneumatic relay 8 and directional circuit controller DCC is moved to the left-hand position connecting inductors 2a and 2b to amplifier AM and supplying energy to terminals B32 and C. When valve CV1 is operated the operator would also depress acknowledging switch ACK which causes the acknowledging relay SP to be picked up over its previously traced pick-up circuit and then retained picked up over its previously traced stick circuit when switch ACK is restored to its normal position since the decoding relays A, R and L are now all released. Relay S is also picked up when energy is applied to terminals B32 and C because the decoding relays are all released. With relay S picked up the magnet valve 61 is energized over the fourth circuit path which includes front contact 99 of relay S, contacts 83b and 83c of the fourth contact group of speed governor GV and resistor SG1. With magnet 61 energized pressure is applied to the piston chamber of repeater valve PV, causing valve 69 to be closed to blank pressure from pipe 31 to pipe 70 and warning whistle 71 is silent.

The operator next places the manual brake valve at a brake application position causing suppression switch SR to close contacts 103 and 104 and brake control magnet valve MV is energized over its alternative circuit and the automatic brake application valve BA is actuated to its brake release position.

Since magnet 61 is energized pressure is now supplied to the power off switch PS closing contacts 44, 45, 46 and 47. The closing of contacts 46 and 47 applies motive power to the master controller for operating the vehicle, and the closing of contacts 44 and 45 energizes timing relay TR in multiple with magnet 61, the connection to relay TR being completed at front contacts 87 and 88 of relay SP. Brake control magnet valve MV is now energized over its normal circuit including front contacts 91 and 92 of relay TR and the operator may move the manual brake valve to the release position.

It is to be noted that when energy is first applied to terminals B32 and C, magnet 72 of the whistle magnet valve AMV is energized and pressure is supplied from supply pipe 31 to pipe 74 and the acknowledging whistle 76 is sounded. The circuit for magnet valve 72 extends from terminal B32 over contact 54 of acknowledging

switch ACK, wire B2, back contacts 55, 56, 57, 58 and 112 of relays P, A, R, L and SP, respectively, and winding of magnet valve 72 to terminal C. When the operator depresses switch ACK to pick up relay SP magnet valve 72 is deenergized and whistle 76 is rendered silent.

Warning relay WL is energized and picked up due to the voltage drop across resistor SG1 so that signal unit W is dark. The signal unit 11, however, is illuminated since the decoding relays 10 are all released.

The apparatus is now in service and the vehicle can be operated under the control of the train operator.

When the vehicle is moving over a track section under clear traffic conditions and current of the 180 code rate is received, decoding relays A and L are picked up due to operation of the code following relay MR and relay R is picked up by its alternative circuit including front contacts 20 and 22 of relay A. The picking up of relays L and R at this time effects no particular function and need not be further considered under clear traffic conditions. The picking up of decoding relay A completes the operating circuit for the cab signal unit 35 and that unit displays a clear traffic condition and a speed limit of 35 miles per hour. Decoding relay A also completes at its front contacts 84 and 42 the first circuit path by which magnet 61 of the speed warning magnet valve AMV and relays TR and WL are energized, such circuit path including the first group of contacts of the speed governor GV. With timing relay TR picked up closing front contacts 91 and 92 the brake control magnet MV is retained energized and the brake application valve BA occupies its brake release position. Thus the vehicle may under clear traffic conditions operate at speeds up to 35 miles an hour under manual control of the train operator. Assume that the vehicle exceeds the speed of 35 miles per hour, contact 88a of the first group of speed governor contacts is opened, and relay WL is deenergized to cause the warning signal W to be illuminated. If the operator reduces the speed the warning signal W goes out when contact 88a is reclosed. If the speed continues to increase and reaches 36 1/4 miles per hour, contacts 88b and 88c are opened to deenergize magnet 61 and relay TR. Magnet valve 61 at once causes operation of the power off controller PS to open at contacts 46 and 47 the connection for the motive power so that the train operator cannot apply power to increase the speed of a vehicle. The repeater valve PV is also operated to cause the warning signal 71 to be sounded. Timing relay TR is not released to open front contacts 91 and 92 until the end of its slow release period and hence an automatic brake application is not effected until the end of the slow release period of timing relay TR subsequent to the sounding of the warning whistle 71. This slow release period of timing relay TR may be of the order of two and one-half seconds. If the operator acts to move the master controller to its power off position closing contacts 102 and 105 and also places the manual brake valve at a brake application position to operate suppression switch SR and close contacts 103 and 104 during this delay period of two and one-half seconds before timing relay TR is released to actuate magnet valve MV, the magnet valve MV is retained energized over its alternative circuit and automatic application of the train brake is suppressed. Hence the warning signal indication W is first

displayed and the warning whistle 71 is next sounded to warn the operator to reduce the speed and an automatic brake application is effected after two and one-half seconds unless the operator takes suitable steps to reduce the train speed.

In the event the vehicle is moving over a track section for which approach-medium traffic conditions in advance prevail and current of the code rate of 120 is received so that decoding relays R and L are picked up and decoding relay A is released, the approach-medium signal unit 17 of the cab signal is displayed. Magnet valve 61 and relays TR and WL are now energized over the second circuit path which includes the second group of contacts of the speed governor, and the vehicle may be operated at speeds up to 25 miles per hour under manual control. If the vehicle speed exceeds 25 miles per hour to open contact 81a of the second group of contacts of the speed governor, relay WL is deenergized and the warning signal W is displayed. If the train speed continues to increase and exceeds 26 miles per hour, contacts 81b and 81c are opened to deenergize magnet 61 and relay TR. Warning whistle 71 is operated the same as previously explained and an automatic brake application is effected at the end of the two and one-half seconds slow release period of relay TR unless the operator acts to shut off power causing contacts 102 and 105 to be closed and places the manual brake valve at a brake applying position causing contacts 103 and 104 of the suppression switch SR to close so that the magnet valve MV is energized over its alternative circuit. As soon as the speed of the vehicle is reduced to less than 25 miles per hour so that the second group of speed governor contacts are reclosed magnet valve 61 and relays WL and TR are reenergized and the vehicle can then be operated under manual control as previously explained.

When the vehicle passes into a track section having approach traffic conditions and current of the 75 code is received causing decoding relay L to be picked up and decoding relays R and A to be released the approach cab signal unit 17 is illuminated to display an approach cab signal and to indicate the speed limit of 17 miles per hour for the vehicle. Magnet valve 61 and relays TR and WL are now energized over the third circuit path which includes the third group of speed governor contacts. In the event the vehicle exceeds the speed of 16½ miles per hour under approach traffic conditions causing contact 82a of the third group of contacts to be operated to an open position relay WL is deenergized with the result that the warning signal indication W is displayed. If the train speed continues to increase and exceeds 17½ miles per hour, contacts 82b and 82c are opened to deenergize magnet 61 and relay TR. Warning whistle 71 is sounded and automatic brake application is effected at the end of the two and one-half seconds release period of timing relay TR unless the operator takes steps to shut off power and place the manual brake valve at the brake applying position so that the magnet valve MV is retained energized over its alternative circuit.

In case the vehicle enters an occupied track section and all decoding relays, A, R and L are released due to the absence of coded current, the slow cab signal unit 11 is illuminated to display a slow indication and to indicate the maximum of 11 miles per hour. Magnet valve 61 and relays TR and WL are now energized over a fourth circuit path which includes the fourth

group of contacts of the speed governor and front contact 99 of relay S. Since relay S is automatically picked up in response to this slow traffic condition and since the circuit for relay TR includes either back contacts 86 and 88 of relay S or front contacts 87 and 89 of acknowledging relay SP the most restrictive indication must be acknowledged by the operator in order to energize relay TR and avoid an automatic brake application at the end of the two and one-half seconds slow release period of timing relay TR. It is to be noted that when relays A, R and L are all released due to this slow traffic condition magnet valve 72 of the second unit of the warning magnet valve AMV is energized over the previously traced circuit to cause acknowledging whistle 76 to be sounded. To acknowledge this most restrictive indication, the operator depresses the acknowledging switch ACK to complete the pickup circuit of relay SP and then restores switch ACK to its normal position during the two and one-half seconds delay period. Relay SP when picked up to close front contacts 87 and 89 retains the circuit for the timing relay TR closed. Hence after such acknowledgment of the most restrictive indication the vehicle can proceed at a speed not to exceed 11 miles per hour. In the event the speed of 10 miles per hour is reached under slow traffic conditions so that contact 83a is opened the relay WL is released and warning signal W is displayed. If the train speed continues to increase and exceed 11 miles per hour, contacts 82b and 82c are opened to deenergize magnet 61 and relay TR. With magnet 61 deenergized the warning whistle 71 is sounded and power-off switch PS is operated as previously explained. Timing relay TR is released at the end of its two and one-half seconds slow release period and magnet valve MV is de-energized unless the operator takes steps to complete the alternative circuit for magnet valve MV by placing the master controller at the power off position and placing the manual brake valve at the brake applying position.

It is to be pointed out that in the event magnet valve MV is deenergized and an automatic brake application is effected through brake application valve BA, magnet valve MV is not at once reenergized when the train speed has been reduced closing the contacts of the respective contact group of the speed governor because power off switch controller PS is opened due to the operation of valve BA and relay TR cannot be reenergized until controller PS is reclosed. Hence the operator must follow the same procedure used in suppressing an automatic brake application in order to release the automatic brake application. That is, the operator places the master controller at the power off position closing contacts 102 and 103 and moves the manual brake valve to a brake application position operating suppression switch SR to close contacts 103 and 104. Magnet valve MV is then energized over its alternative circuit and brake valve BA is reset, after which the power off controller PS is closed and relay TR reenergized.

In the event the vehicle moves from train control territory to nontrain control territory and in so doing passes over a track section which supplies the special 240 code rate, relay P is automatically picked up in response to operation of relay MR at the 240 code rate and relay P on picking up closing front contacts 106 and 109 completes its stick circuit by which it is retained energized subsequent to the train passing beyond

- the special track section and moving through non-train control territory. When relay P is picked up the operating circuit for signal unit NS is completed and that unit is illuminated to display 5 a purple color to indicate operation of the vehicle in nontrain control territory. Relay P on picking up to close front contacts 110 and 111 also completes the alternative circuit by which relays TR and WL and magnet valve 61 are retained 10 energized so that a vehicle may operate in non-train control territory without the speed limits prescribed by the speed governor GV being enforced.

When the vehicle returns to train control 15 territory the decoding relays A, R and L are energized according to the code rate of the track section entered, the cut-out relay P is deenergized and released and the apparatus is at once restored to its normal condition.

- 20 In the event it is desired to manually effect the cut-out condition of the apparatus one member of the train crew actuates the cut-out switch CO at the same time another member of the train crew operates the acknowledging switch ACK, 25 the cut-out switch being located remote from switch ACK. A pick-up circuit is thus formed for the cut-out relay P which circuit includes terminal B32, back contacts 24, 30, 51 and 36 of relays A, R, SP and L, respectively, wire S1, contact 52 of acknowledging switch ACK when depressed, wire SP1, wire SP2, contact 113 of cut-out switch CO when operated, wire P1, resistor 108, winding of relay P, wire NP, wire NP1, contact 114 of switch CO, wire NSF, and contact 53 of acknowledging switch ACK to terminal C. 30 With cut-out relay P picked up it is then retained energized over its previously described stick circuit. This operation of acknowledging switch ACK may also pick up acknowledging relay SP, 35 but the stick circuit for relay P would be retained complete over front contact 60 of relay SP. A lamp 115 located at the cut-out switch CO is connected across wires SP2 and NP1 and is illuminated in multiple with the winding of relay P 40 while the acknowledging switch ACK and the cut-out switch CO are depressed and lamp 115 thus indicates to the train member operating cut-out switch CO the position of the acknowledging switch ACK.
- 45 Although we have herein shown and described only one form of railway traffic controlling apparatus embodying our invention, it is to be understood that various changes and modifications 50 may be made therein within the scope of the appended claims without departing from the spirit and scope of our invention.

Having thus described our invention, what we claim is:

1. In a railway traffic controlling apparatus 60 for use with train carried receiving means responsive to current coded at any one of a plurality of different code rates for energizing a particular decoding relay for each of said code rates to establish in turn a particular cab signal 65 indication for each of the code rates, the combination comprising, a train operated speed governor having a contact for each of said code rates and each of which contacts is biased to a closed position and operated to an open position 70 at speeds above a speed prescribed for the corresponding code rate, a slow release timing relay effective to control at its front contact a normal circuit for energizing a brake control magnet valve, a warning relay effective to control over its back contact a warning cab signal indication, a

warning magnet valve effective when deenergized to cause a warning whistle to sound; circuit means having a plurality of multiple circuit paths one for each of said code rates for energizing said timing relay, said warning relay and said warning magnet valve; each of said circuit paths including in series a front contact of the decoding relay and the speed governing contact of the same code rate as that with which the circuit path is associated, a manually operable suppression switch, and an alternative circuit including a contact of said suppression switch to energize said brake control magnet valve.

2. In railway traffic controlling apparatus for use with train carried receiving means responsive to current coded at any one of three different code rates for selectively controlling three decoding relays and in turn establishing one of three cab signal indications according to the code rate of such current, the combination comprising, 20 a train operated speed governor having three contacts one for each of said code rates and each of which contacts is biased to a closed position and operated to an open position at speeds above a speed prescribed for the corresponding code 25 rate, a slow release timing relay to control over its front contact a brake control magnet valve, a warning relay to control over its back contact a warning cab signal indication, a whistle magnet valve to control when deenergized a warning air 30 whistle; and circuit means having three multiple paths each of which paths includes a front contact of a selected one of said decoding relays and the contact of said speed governor which corresponds to the same code rate as the selected decoding relay for energizing said timing relay, said 35 warning relay and said warning whistle magnet valve.

3. In railway traffic controlling apparatus for use with train carried receiving means responsive to current coded at any one of a plurality of different code rates for selectively controlling a corresponding number of decoding relays and in turn controlling a corresponding number of cab signal indications according to the code rate of such current, the combination comprising, a train operated speed governor having a plurality of contacts one for each of said code rates and each of which contacts is adjusted for operation at a speed prescribed for the corresponding code 40 rate, a slow release timing relay, a brake control magnet valve controlled over a front contact of said timing relay, a warning relay, a warning cab signal unit controlled over a back contact of said warning relay, a warning magnet valve effective when deenergized to cause the sounding of a warning whistle; and circuit means having a plurality of parallel paths one for each of said code rates for energizing said timing relay, said 45 warning relay and said warning magnet valve; and each of said circuit paths including in series a front contact of a particular decoding relay and the speed governor contact corresponding to the same code rate as said particular decoding relay.

4. In railway traffic controlling apparatus for 50 use with train carried receiving means responsive to current coded at any one of a plurality of different code rates for energizing a particular decoding relay for each of said code rates to establish in turn a particular cab signal indication for 55 each of the code rates, the combination comprising, a train operated speed governor having a contact for each of said code rates and each of which contacts is biased to a closed position and operated to an open position at speeds above a 60

speed prescribed for the corresponding code rate, a slow release timing relay effective to control over its front contact a normal circuit for energizing a brake control magnet valve, a warning magnet valve effective when deenergized to cause a warning whistle to sound; circuit means having a plurality of multiple circuit paths for energizing said timing relay and said warning magnet valve in parallel and each of which circuit paths includes in series a front contact of a particular decoding relay and the speed governor contact for the code rate at which said particular decoding relay is energized, a manually operable suppression switch controller, and an alternative circuit including a contact of said controller for energizing said brake control magnet valve.

5. In railway traffic controlling apparatus for use with train carried receiving means responsive to current coded at any one of three different code rates for energizing selected ones of three decoding relays and in turn governing three different cab signal indications according to the code rate, the combination comprising, a train operated speed governor having three groups of contacts one for each code rate, the contacts of each contact group adjusted for operation at a train speed prescribed for the associated code rate and with a prescribed speed differential between a first and a second contact of the group, a warning relay adapted to govern over its contact a warning cab signal unit, a slow release timing relay adapted to govern over its contact a brake control magnet valve, a warning whistle magnet valve adapted when deenergized to cause a warning air whistle to sound, circuit means having three multiple circuit paths for energizing said warning magnet valve and said timing relay in parallel; each of said circuit paths including in series a front contact of a selected one of said decoding relays, said second contact of the contact group of the speed governor corresponding to the code rate at which said selected relay is energized and a resistor; and three circuit connections to connect said warning relay across said resistors and each of which circuit connections includes said first contact of the contact group a contact of which group is interposed in the same multiple circuit path as the 50 resistor.

6. In railway traffic controlling apparatus for use with train carried receiving means responsive to current coded at any one of a plurality of different code rates for energizing a particular decoding relay for each of said code rates to establish in turn a particular cab signal indication for each of the code rates, the combination comprising, a train operated speed governor having a contact for each of said code rates and each of which contacts is biased to a closed position and operated to an open position at speeds above a speed prescribed for the corresponding code rate, a slow release timing relay effective to control over its front contact a brake control magnet valve, a warning electromagnetic device effective when deenergized to cause a warning cab signal indication; circuit means having a plurality of multiple circuit paths one for each of said code rates to energize said timing relay and said electromagnetic device and each of which circuit paths includes in series a front contact of a particular decoding relay and the speed governor contact for the code rate at which said particular decoding relay is energized, a manually operable suppression switch controller, and

an alternative circuit including a contact of said suppression controller for energizing the brake control magnet valve.

7. In railway traffic controlling apparatus for use with train carried receiving means responsive to current coded at any one of three different code rates for energizing selected ones of three decoding relays according to the code rate and to release all such decoding relays in response to absence of such coded current for in turn governing four cab signal indications one for each of said code rates and a fourth one for the absence of coded current, the combination comprising, a train operated speed governor having four groups of contacts one group for each of said code rates and a fourth one for the absence of coded current, said contact groups set for operation at different preselected train speeds, a warning electromagnetic device effective when deenergized to cause a warning cab signal indication, a slow release timing relay to control over its front contact a brake control magnet valve, circuit means having three multiple paths each of which includes a front contact of a selected one of said decoding relays and a contact of the contact group for the code rate at which said selected decoding relay is energized to energize said electromagnetic device and said timing relay, circuit means including a back contact of each of said decoding relays and a contact of the contact group corresponding to the absence of coded current to energize said warning electromagnetic device, an acknowledging relay controlled over a back contact of each of said decoding relays and a contact of a manually operable acknowledging switch, and means including a front contact of said acknowledging relay to connect the timing relay to said last mentioned circuit means.

8. In railway traffic controlling apparatus for use with train carried receiving means responsive to current coded at a particular code rate for energizing a decoding relay to govern a corresponding cab signal indication, the combination comprising, a train operated speed governor having a contact group set for operation at a particular train speed with a prescribed speed differential between a first and a second contact of the group, a slow release timing relay adapted to control over its front contact a brake control magnet valve, a warning relay adapted to control over its back contact a warning cab signal indication, a warning magnet valve adapted when deenergized to actuate a warning air whistle, circuit means including a front contact of said decoding relay, said second contact of said contact group of the speed governor and a resistor to energize said timing relay and said warning magnet valve in parallel, and means including said first contact of said contact group of the speed governor to connect said warning relay across said resistor.

9. In railway traffic controlling apparatus for use with train carried receiving means responsive to current coded at a particular code rate for energizing a decoding relay to govern a corresponding cab signal indication, the combination comprising, a train operated speed governor having a contact group set for operation at a particular train speed with a prescribed speed differential between a first and a second contact of the group, a slow release timing relay adapted to control over its front contact a brake control magnet valve, a warning relay adapted to control over its back contact a warning cab signal indi-

- cation, a warning magnet valve effective when energized to close a power off switch controller and when deenergized to open such power off switch controller and to actuate a warning air whistle; a control circuit including a front contact of said decoding relay, said second contact of said control group of the speed governor and a resistor in series to energize said warning magnet valve; means including a normally closed contact 5 of said power off switch controller to connect said timing relay to said control circuit to energize said timing relay in multiple with the warning magnet valve, and means including said first contact of said contact group in series with said 10 second contact of the contact group to connect said warning relay across said resistor to energize the warning relay due to the voltage drop across said resistor.
19. In railway traffic controlling apparatus for use with train carried receiving means responsive to current coded at a particular code rate for energizing a decoding relay to govern a corresponding cab signal indication, the combination comprising, a train operated speed governor 15 having a contact group set for operation at a particular train speed with a prescribed speed differential between a first and a second contact of the group, a slow release timing relay adapted to control over its front contact a brake control magnet valve, a warning relay adapted to control over its back contact a warning cab signal indication, a warning magnet valve effective when energized to close a power off switch controller and when deenergized to open such power off switch controller and to actuate a warning air 20 whistle; a control circuit including a front contact of said decoding relay, said second contact of said control group of the speed governor and a resistor in series to energize said warning magnet valve; means including a normally closed contact 25 of said power off switch controller to connect said timing relay to said control circuit to energize said timing relay in multiple with the warning magnet valve, means including said first contact of said contact group in series with said second contact of the contact group to connect said warning relay across said resistor to energize the warning relay due to the voltage drop across said resistor, a manually operable suppression switch controller, and an alternative circuit including a contact of said suppression switch controller to energize said brake control magnet valve independent of said timing relay. 30
11. In railway traffic controlling apparatus for use with train carried receiving means responsive to current coded at any one of a plurality of different code rates for energizing a particular decoding relay and in turn governing a particular cab signal indication in response to each of said code rates, the combination comprising, a train operated speed governor having a contact group for each of said code rates, a slow release timing relay, a circuit including a front contact of said timing relay to energize a brake control magnet valve, a warning relay, a warning cab signal unit controlled over a contact of said warning relay, a warning magnet valve, a warning whistle governed by said warning magnet valve and silent when the warning magnet valve is energized and sounded when that magnet valve is deenergized, circuit means having a plurality of multiple circuit paths one for each of said code rates for energizing said timing relay and said warning magnet valve in parallel; each of said circuit 35 paths including a front contact of a particular decoding relay, a contact of the contact group of the speed governor for the code rate at which said particular decoding relay is energized and a resistor; and a plurality of circuit connections to connect said warning relay across said resistors and each of which circuit connections includes a contact of the contact group having a contact interposed in the same circuit path as that resistor. 40
12. In railway traffic controlling apparatus for use with train carried receiving means responsive to current coded at any one of a plurality of different code rates corresponding to different traffic conditions for energizing a plurality of decoding relays at a particular combination for each of said traffic conditions, the combination comprising, a special cut-out decoding relay coupled to said receiving means for effective energization in response to current coded at a code rate different from said plurality of code rates, a stick circuit including a back contact of each of said plurality of decoding relays to energize said cut-out decoding relay, a special cut-out cab signal, and an operating circuit including a front contact of said cut-out decoding relay to operate said cut-out cab signal. 45
13. In railway traffic controlling apparatus for use with train carried receiving means responsive to current coded at any one of a plurality of different code rates corresponding to different traffic conditions for energizing a plurality of decoding relays at a particular combination for each of said traffic conditions for in turn selectively governing a cab signal to display a particular indication for each of said different traffic conditions, the combination comprising, a special cut-out decoding relay coupled to said receiving means for effective energization and picking up of that relay only in response to current coded at a code rate different from said plurality of code rates, a stick circuit including a back contact of each of said plurality of decoding relays for retaining said cut-out decoding relay picked up, an operating circuit including a back contact of each of said plurality of decoding relays and a back contact of said cut-out decoding relay to cause said cab signal to display a slow or most restrictive indication, and another operating circuit including a front contact of said cut-out decoding relay to cause said cab signal to display a cut-out indication. 50
14. In railway traffic controlling apparatus for use with train carried receiving means responsive to current coded at any one of a plurality of different code rates corresponding to different traffic conditions for energizing a particular one of a plurality of decoding relays for each of said traffic conditions, the combination comprising, a special cut-out decoding relay coupled to said receiving means for effective energization in response to current coded at a code rate different from said plurality of code rates, a stick circuit including a back contact of each of said plurality of decoding relays to energize said cut-out decoding relay, an electromagnetic device effective when deenergized to cause an automatic application of the train brakes, means including contacts of said plurality of decoding relays effective to energize said electromagnetic device for each of said traffic controlled combinations of such decoding relays, and an alternative circuit including a front contact of said cut-out decoding relay to energize said electromagnetic device. 55
15. In railway traffic controlling apparatus for use with train carried receiving means responsive to current coded at any one of a plurality of different code rates corresponding to different traffic conditions for energizing a particular one of a plurality of decoding relays for each of said traffic controlled combinations of such decoding relays, and an alternative circuit including a front contact of said cut-out decoding relay to energize said electromagnetic device. 60

to current coded at any one of a plurality of different code rates corresponding to different traffic conditions for energizing a particular one of a plurality of decoding relays for each of said traffic conditions, the combination comprising, a special cut-out decoding relay coupled to said receiving means for effective energization in response to current coded at a code rate different from said plurality of code rates, a stick circuit including a back contact of each of said plurality of decoding relays to energize said cut-out decoding relay, a train operated speed governor having a contact for each of said plurality of code rates and each of which contacts is biased to a closed position and operated to an open position at speeds above a speed prescribed for the corresponding code rate, a slow release timing relay effective to control over its front contact a brake control magnet valve, a warning magnet valve effective when deenergized to cause a warning whistle to sound, circuit means having a plurality of multiple circuit paths for energizing said timing relay and said warning magnet valve in parallel, each of said circuit paths including in series a front contact of a particular decoding relay and the speed governor contact corresponding to the code rate at which that particular decoding relay is energized, and an alternative circuit including a front contact of said cut-out decoding relay to energize said warning magnet valve and said timing relay.

16. In railway traffic controlling apparatus for use with train carried receiving means responsive to current coded at a particular code rate in response to a given traffic condition for energizing a traffic controlled decoding relay for in turn causing a cab signal to display an indication corresponding to such traffic condition, the combination comprising, an electromagnetic device effective when deenergized to cause an automatic application of the train brakes, a first circuit including a front contact of said decoding relay to energize said electromagnetic device, a cut-out decoding relay coupled to said receiving means for energization and picking up of such cut-out relay only in response to current coded at a rate different from said particular code rate, a stick circuit including a back contact of said traffic controlled decoding relay to retain said cut-out decoding relay picked up, an operating circuit including a back contact of each of said decoding relays to cause said cab signal to display a slow indication, another operating circuit including a back contact of said traffic controlled decoding relay and a front contact of said cut-out decoding relay to cause said cab signal to display a cut-out indication, and an alternative circuit including a front contact of said cut-out decoding relay to energize said electromagnetic device.

17. In railway traffic controlling apparatus for use with train carried receiving means responsive to current coded at a particular code rate in response to a given traffic condition for energizing a traffic controlled decoding relay for in turn causing a cab signal to display an indication corresponding to such traffic condition, the combination comprising, an electromagnetic device effective when deenergized to cause an automatic application of the train brakes, a first circuit including a front contact of said decoding relay to energize said electromagnetic device, a cut-out decoding relay coupled to said receiving means for energization and picking up of such cut-out relay only in response to current coded at a rate

different from said particular code rate, a stick circuit including a back contact of said traffic controlled decoding relay to retain said cut-out decoding relay picked up, an acknowledging relay, a manually operable acknowledging switch, a pick-up circuit including a back contact of said traffic controlled decoding relay and a contact of said switch when operated to pick up said acknowledging relay, a stick circuit including a back contact of each of said two decoding relays and a normally closed contact of said switch to retain said acknowledging relay picked up, a second circuit including a front contact of said acknowledging relay to energize said electromagnetic device, and a third circuit including a front contact of said cut-out decoding relay to energize said electromagnetic device.

18. In railway traffic controlling apparatus for use with train carried receiving means responsive to current coded at a particular code rate in response to a given traffic condition for energizing a traffic controlled decoding relay for in turn causing a cab signal to display an indication corresponding to such traffic condition, the combination comprising, an electromagnetic device effective when deenergized to cause an automatic application of the train brakes, a first circuit including a front contact of said decoding relay to energize said electromagnetic device, an acknowledging relay, a manually operable acknowledging switch, an acknowledging whistle magnet valve effective when energized to cause an acknowledging whistle to sound, a circuit including a back contact of said acknowledging relay and a back contact of said decoding relay to energize said acknowledging whistle magnet valve, a pick-up circuit including a back contact of said decoding relay and a contact of said switch when operated to pick up said acknowledging relay, a stick circuit including a back contact of said decoding relay and a normally closed contact of said switch to retain said acknowledging relay picked up, and a second circuit including a front contact of said acknowledging relay to energize said electromagnetic device.

19. In railway traffic controlling apparatus for use with a train having the usual manual brake valve and provided with train carried receiving means responsive to current coded at a given rate for energizing a decoding relay, the combination comprising, a brake control magnet valve effective when energized to control an automatic brake application valve to a release position and when deenergized to control such brake application valve to a brake application position, a suppression switch biased to an open position and operable to a closed position in response to a brake application position of the manual brake valve, a warning magnet valve effective when deenergized to cause the sounding of a warning whistle, a power off switch controlled to a closed position when said warning magnet valve is energized and to an open position when that magnet valve is deenergized and when said automatic brake application valve is controlled to its brake application position, a timing relay, a normal circuit including a front contact of said timing relay to energize said brake control magnet valve, a control circuit including a front contact of said decoding relay to energize said warning magnet valve, means including a closed position contact of said power off switch to connect said timing relay to said control circuit to energize said timing relay in multiple with said warning magnet valve, and an alternative circuit including a closed

position contact of said suppression switch to energize said brake control magnet valve.

20. In railway traffic controlling apparatus for use with train carried receiving means responsive to current coded at a particular code rate in response to a given traffic condition for energizing a traffic controlled decoding relay for in turn causing a cab signal to display an indication corresponding to such traffic condition, the combination comprising, an electromagnetic device effective when deenergized to cause an automatic application of the train brakes, a first circuit including a front contact of said decoding relay to energize said electromagnetic device, a cut-out decoding relay coupled to said receiving means for energization and picking up of such cut-out

relay only in response to current coded at a rate different from said particular code rate, a stick circuit including a back contact of said traffic controlled decoding relay to retain said cut-out decoding relay picked up, a first and a second 5 manually operable switch located on the train remote from each other, a special pick-up circuit including in series a contact of each of said first and second manually operable switch to energize said cut-out relay, and an alternative circuit including a front contact of said cut-out decoding relay to energize said electromagnetic device.
